UNITED STATES PATENT OFFICE.

OLIVER H. SEBRING, OF SEBRING, OHIO.

DESIGN FOR A SUGAR-BOWL OR SIMILAR ARTICLE.

50,821.

Specification for Design.

Patented May 22, 1917.

Application filed March 4, 1916. Serial No. 82,248. Term of patent 7 years.

To all whom it may concern:

Be it known that I, OLIVER H. SEBRING, a citizen of the United States, residing at Sebring, in the county of Mahoning and State of Ohio, have invented a new, original, and ornamental Design for a Sugar-Bowl or Similar Article, of which the following is a specification, reference being had to the accompanying drawing, forming part thereof.

Figure 1 is a side elevation of a sugar bowl, with a part of the rim in section, showing my new design; and Fig. 2, a plan view thereof showing half of the cover broken away.

I claim:

The ornamental design for a sugar bowl or similar article as shown.

OLIVER H. SEBRING.
